UNITED STATES PATENT OFFICE

135,329

DESIGN FOR AN OUTBOARD MOTOR

Elmer C. Kiekhaefer, Cedarburg, Wis., assignor to Kiekhaefer Corporation, Cedarburg, Wis., a corporation of Wisconsin

Application December 18, 1940, Serial No. 97,431

Term of patent 14 years

To all whom it may concern:

Be it known that I, Elmer C. Kiekhaefer, a citizen of the United States, residing at Cedarburg, county of Ozaukee, and State of Wisconsin, have invented a new, original, and ornamental Design for an Outboard Motor, of which the following is a specification, reference being had to the accompanying drawing, forming a part thereof.

I claim:

The ornamental design for an outboard motor, as shown.

ELMER C. KIEKHAEFER.
